UNITED STATES PATENT OFFICE.

LLOYD CHAMPLIN EDDY, OF BUFFALO, NEW YORK.

ELECTRIC LOG.

1,248,637.

specification of Letters Patent.

Patented Dec. 4, 1917.

Application filed December 4, 1916. Serial No. 135,046.

To all whom it may concern:

Be it known that I, LLOYD C. EDDY, a citizen of the United States, residing at Buffalo, in the county of Erie and State of New York, have invented certain new and useful Improvements in Electric Logs, of which the following is a specification.

My invention relates to electrically operated heating logs, which, during operation, 10 resemble glowing or burning wood logs, in a highly realistic and attractive manner.

An important object of the invention is to provide apparatus of the above mentioned character, which is simple in construction, 15 inexpensive to manufacture, and convenient in use.

Other objects and advantages of the invention will be apparent during the course of the following description.

20 In the accompanying drawings forming a part of this specification and in which like numerals are employed to designate like parts throughout the same,

Figure 1 is a side elevation of apparatus 25 embodying the invention, half being shown in longitudinal section,

Fig. 2 is an end elevation of the same, half shown in transverse section, and,

Fig. 3 is a diagrammatic view of the heating coils and circuits therefor.

In the drawings, wherein for the purpose of illustration is shown a preferred embodiment of my invention, the body portion of the apparatus is represented by the numeral 35 5, and is formed of insulating material such as porcelain, glass or the like. This body portion is in the form of three tubular logs 6, stacked as shown. The logs are provided upon their exterior with depressions 7 and 40 are further provided with apertures 8. Particular attention is called to the fact that the depressions 7 are disposed in or upon the exterior surface of the wall of the support or log, and these depressions do not pass 45 or cut through said wall to lead into the interior of the hollow support or log, whereby the appearance of the log is not impaired.

Arranged within the depressions 7 at suitably spaced intervals are heating coils 9 of 50 high resistance, which are adapted to glow or be luminescent. These coils are disposed within the exterior depressions, and are thereby arranged exteriorly of the outer surface of the wall of the support or log. These 55 heating coils 9 are connected in series with a wire 10 by means of conductors 11, ar-

ranged within the apertures 8. The opposite end of the wire 10 is connected with the wire 11 which is also connected with the wire 10, as shown in Fig. 3. A switch 12 is connected in the wire 10, and is preferably arranged upon the exterior of one of the lower logs, and secured thereto by any suitable means, as shown. Arranged within the interior of the logs is an electric bulb 13, 60 which is connected in series with the wire 11, as shown. The wires 10 and 11 are adapted for connection with the opposite poles of a source of current.

When the switch 12 is closed it is obvious 70 that current will flow through the wire 10 and the heating coils 9 connected in series therewith and through a portion of the wire 11 back to the opposite pole of the source of current. A portion of the current will also 75 flow through a portion of the wire 10, electric bulb 13, and through the wire 11 back to the opposite pole of the source of current. The bulb 13 may thus be made to glow while the heating coils glow, to illuminate the logs, 80 while it is to be understood that satisfactory results may be obtained by omitting the electric bulb. I have found that the glowing coils, arranged at spaced intervals, preferably in the depressions in the logs, produce 85 an exceedingly realistic effect, it appearing as if the logs were ignited at intervals.

The logs may be made sufficiently large for use in a fire-place, or they may be made smaller and used upon a table for heating 90 plates or the like. The invention is not restricted to any particular use of the construction.

It is to be understood that the form of my invention herewith shown and described is 95 to be taken as preferred example of the same, and that various changes in the shape, size, and arrangement of parts may be resorted to without departing from the spirit of the invention or the scope of the subjoined claims.

Having thus described my invention, I claim:

1. The combination with a support formed of insulating material and simulating a log, 100 of a plurality of spaced heating coils of high resistance arranged upon the exterior of the outer surface of the wall of said support of the log and secured thereto and adapted to glow upon the passage of current there-through, and means for supplying current 110 to the coils.

2. The combination with a support formed of insulating material and simulating a log and having depressions formed upon the exterior surface of the wall of said support and which depressions do not cut through said wall and lead to the interior of the support, of a plurality of spaced heating coils of high resistance secured within the depressions and adapted to glow upon the 10 passage of current therethrough, and means for supplying current to the coils.

3. The combination with a support formed of insulating material and simulating a log and provided with exterior depressions upon the exterior surface of the wall of said support and which depressions do not cut through said wall and lead to the interior of the support and apertures, a plurality of spaced heating coils of high resistance arranged within the depressions and adapted 20 to glow upon the passage of current therethrough, circuits connected with the coils and passing through the apertures and ar-

ranged within the log, and a switch connected in the circuit to open and close it. 25

4. The combination with a support formed of insulating material and simulating a log and provided with exterior depressions upon the exterior surface of the wall of said support and which depressions do not cut through said wall and lead to the interior of the support and apertures, of a plurality of spaced heating coils of high resistance arranged within the depressions and adapted to glow upon the passage of current therethrough, circuits connected with the coils and passing through the apertures and arranged within the log, an electric bulb connected in one circuit, and a switch to open and close the circuit. 35

In testimony whereof I affix my signature
in presence of two witnesses.

LLOYD CHAMPLIN EDDY.
